UNITED STATES PATENT OFFICE.

CLARENCE E. FRAZIER AND HELMER R. LINDQUIST, OF CHICAGO, ILLINOIS.

AIR VENT AND HUMIDIFIER.

Application filed July 9, 1923. Serial No. 650,235.

To all whom it may concern:

Be it known that we, CLARENCE E. FRAZIER and HELMER R. LINDQUIST, citizens of the United States, residing at Chicago, in the county of Cook and State of Illinois, have invented a certain new and useful Improvement in Air Vents and Humidifiers, of which the following is a full, clear, concise, and exact description, reference being had to the accompanying drawings, forming a part of this specification.

Our invention relates to an improved air vent and humidifier for radiators and the like.

15 The moisture carrying capacity of air increases rapidly with the temperature and hence as air in a room or other space is warmed an increased amount of moisture in the air is necessary to maintain the desired 20 humidity. If the amount of moisture is not increased that originally present generally becomes insufficient as the temperature rises. Low humidities are not only uncomfortable but they are detrimental to health. 25 Furniture and other contents of a room are frequently damaged by improper humidification.

The commercial advantages of artificial 30 humidification especially in textile mills and the like are well known. The necessity for removing or venting air from steam radiators to maintain high efficiency of the radiating surfaces is also well known.

We are aware that various expedients to 35 the above ends have been heretofore proposed among which are various devices for causing the evaporation of water and others for permitting the escape or discharge of steam from the radiator into the atmosphere. 40 The humidity cannot be readily increased to the desired extent by evaporation and the problem of replenishing the water is presented. Where the escape of steam is permitted constantly during the functioning 45 of the radiator, excessive condensation occurs and it is impossible to maintain the humidity within reasonable limits. Where the steam is discharged through porous material, as has been proposed, we find that condensation and dripping from that point occurs. In attempting to overcome the disadvantages of the devices which are constantly 50 open, pressure controlled devices have been proposed. In venting the air the steam outlets of these devices are opened and permit discharge of the heating fluid regardless of

the temperature of the radiator. A discharge at low temperature is usually not only not necessary but quickly condenses and the disadvantages accompanying the escape of water are well known.

60 Our invention relates to that class of devices in which humidification is accomplished by permitting the escape of steam from the radiator into the atmosphere of the room.

An object of our invention is the provision of a device which will operate automatically to permit such an escape at high 70 temperatures when increased moisture is desirable and to stop such escape at low temperatures when additional moisture is not usually required.

Another object is the provision of novel means for permitting the free escape of air 75 without an appreciable discharge of the heating fluid.

Another object is the provision of a device in which condensation, dripping and 80 the discharge of water is eliminated.

Another provision is a device operated automatically by a change in temperature.

Another object is the provision of a novel, simple and compact structure for accomplishing the foregoing.

85 Other objects and advantages not herein before set forth will appear from the following detailed description and the claims taken with an inspection of the accompanying drawings in which;

90 Figure 1 is a vertical axial section through a device embodying our invention, showing a portion of the radiator to which the device is applied.

95 Fig. 2 is a horizontal section on line 2—2 of Fig. 1.

Fig. 3 is a horizontal section on line 3—3 of Fig. 1, and;

100 Fig. 4 is a reduced and more or less diagrammatic horizontal section on line 4—4 of Fig. 1.

The embodiment of the invention selected for illustration comprises an internal upright cylindrical shell 5 having a detachable base member 6 screw threaded as shown 105 at 7 or otherwise attached to and closing the lower end thereof. Shell 5 is preferably of brass although other suitable material may be employed. Base 6 is likewise preferably though not necessarily of brass, cast or otherwise suitably formed. An external cylindrical shell 8 which may also be of

brass or other suitable material surrounds shell 5 and forms with shell 5 an annular surrounding space or chamber 9 about shell 5. The lower end of shell 8 is attached to base 6 as by threaded engagement at 10. Base 6 has a projecting nipple 12 externally threaded at 13 to be screwed into the usual vent opening 14 in radiator coil, column or section 15. Except as herein-
 10 after referred to the details of the radiator are immaterial. Suffice it to say that vent opening 14 is usually in the end coil opposite the steam inlet end of the radiator and that in the particular device shown
 15 coils or sections 15 are looped and have columns 16 with a space 17 therebetween as shown in Fig. 4. One end of nipple 12 is reduced to pass freely through vent opening 14 and this reduced end projects into
 20 the radiator to prevent condensation that may adhere to the inner surface of the radiator wall from entering the humidifying device. The interior of the radiator communicates with the humidifying device
 25 through a passage 20 extending through nipple 12 and into base 6. Passage 20 and thereby the interior of the radiator, communicates with the interior of shell 5 through a tube 21. Tube 21 extends up
 30 through annular space 9 and enters shell 5 adjacent the top or upper end thereof. Circulation through water accumulation in shell 5 is thereby avoided and the steam is discharged from the device in dry condition and with a minimum of condensation.
 35 A passage 22 controlled by a ball 23 confined between valve seat 24 and a pin or stop 25 secured in base 6 and projecting into passage 20, provides a return from the interior of shell 5 to the radiator.
 40 The upper end of shell 5 is closed by a head 26 threaded or otherwise suitably secured thereon. Head 26 has a circular wall or tubular projection 27 projecting upwardly therefrom and axial disposed relative thereto. A valve containing sleeve 28 having its lower end threaded for threaded engagement with head 26 at 29 and its upper end fitting snugly in tubular projection 27
 45 has slots 30 in its upper end in which a suitable tool is adapted for engagement to threaded the sleeve into place or remove or adjust the same. The upper end of sleeve 28 is counter-bored to provide a valve chamber 31 which communicates through a port or passage 32 with the interior of shell 5. A valve member 33 having an upper flared end the under surface of which is ground for steam-tight engagement with a similarly ground seat 34 is adapted to be seated on the said seat 34 by a spring 35 interposed between valve member 33 and a plug 36 threaded in and closing the upper end of sleeve 28. Plug 36 has a screw driver slot 37. Valve member 33 has a depending

stem or guide portion 38 ground externally to provide flat faces and thereby passages 39, (Fig. 3) for the passage of steam up through passage 32 when valve 33 is unseated from seat 34.

The outer periphery of sleeve 28 has an annular groove 40 which communicates through ports 42 with chamber 31. Mounted at one end in tubular projection 27 is an outlet or steam discharge tube 45 communicating at its upper end with chamber 31 through annular groove 40 and ports 42. A set screw 80 threaded through tubular projection 27, preferably at an angle as shown so that a screw driver may be conveniently engaged therewith from the upper end of 8 when cap 72 is removed, extends into annular groove 40 and limits the upward and also the downward movement or adjustment of sleeve 28 in projection 27. Tube 45 extends radially at its upper end through the interior of shell 8 and then down through annular space 9 between shells 5 and 8 and out through a tubular boss 46 depending from the under side of base 6. A sheet metal tube 48 having a relatively thick lining 50 of felt or other suitable sound deadening material preferably of such character that it will absorb any moisture or condensation in the discharging steam is coupled to the lower end of boss 46 by a coupling nut 52 and projects into space 17 between columns 16 of the radiator sections. By flaring the upper end of lining 50 out over the adjacent flared end of the tube 48 for engagement with boss 46 an exceptionally tight joint is provided at this point, the passage 53 through lining 50 registering with the interior of tube 45.

To insulate the steam discharge tube and prevent condensation of the discharge steam a second metallic tube 54 provided with a heat insulating lining 55 of felt or the like is provided about tube 48 from the point where connection is made with boss 46 to the point where the tube projects into space 17 between the vertical legs of the radiator coils.

Valve member 33 has a port 60 through which the vent or discharge of air from the radiator is permitted when the parts are in the relative position shown.

Within shell 5 is a thermally controlled device comprising preferably a closed container or shell 65 filled or partially filled with a volatile liquid such as alcohol or the like. Shell 65 has a concave lower end resting upon the upper rounded end of a post 66 formed integral with base 6. The upper concave end of container 65 carries a needle valve 70 for closing port 60 upon a rise of water in shell 5 and opening valve 33 against the tension of spring 35 when the temperature has increased sufficiently.

The upper end of shell 8 is closed by a removable cap or cover 72 threaded thereupon which with shell 8 and base 6 completely encloses the operating mechanism 5 of the device.

Outer casing 8 with cap or cover 72 and the formation of base 6 shown excludes cold air from inlet and outlet tubes 21 and 45 and thereby minimizes condensation of the 10 discharging steam.

The operation of the device is as follows:

When the steam is turned on, air in the radiator is forced or pushed through passage 20, tube 21 and into shell 5 from which it escapes or is vented through port 60, chamber 31, ports 42 and tube 45 and passage 53 to atmosphere. Any condensation in shell 5 or any water that collects in the 15 radiator loops and is pushed ahead of the steam into shell 5 collects there and causes float 65 to rise. Stem 70 rises with float 65 and closes vent opening 60. This prevents discharge of water from the radiator.

20 When the steam pressure drops, water or condensation in shell 5 unseats valve 23 and returns to the radiator by way of passages 22 and 20, this return being taken care of by the usual return pipes or in any other 25 suitable or preferred manner. As steam enters shell 5 thermal float 65 is heated until the expansion of the vapor coming off the volatile liquid therein finally forces the concave ends of the float out with a resulting 30 upward movement of the valve 70. This upward movement of the valve 70 first closes vent 60 if it has not already been floated to closed position and then raises valve 33 off its seat 34 against the tension of spring 35. Steam 35 then passes out through tube 45 and passage 53 and is exhausted into space 17 between the upright columns of the radiator loops or coils.

This space is heated by the radiator and we find that discharge of the steam at this 40 point results in thorough distribution of the moisture through the room. Furthermore the discharge of steam is invisible and condensation at the point of discharge is minimized.

45 Shell 8, base 6 and cap 72 enclose shell 5 and tubes 21 and 45 and form a jacket thereabout which excludes cold air. Condensation is thereby minimized and quiet discharge is had. The temperature at which passage 32 is opened by float 65 may 50 be varied as desired by removing cap 72 and threading sleeve 28 into or out of tubular projection 27. This adjustment varies the distance between the seat with 55 which stem 70 cooperates and the upper end of post 66. By threading plug 36 into or out of sleeve 28 the tension of spring 35 may be adjusted. When the radiator 60 is turned off or the pressure drops, float 65 contracts, valve 33 closes, vent 60 opens for 65

the admission of air and any water in shell 5 returns by way of passage 22.

The opening 14 is usually off to one side of space 17 hence tubes 48 and 54 are preferably bent or turned laterally over to the 70 position of said space 17 and then inwardly into said space. Left and right hand discharge tubes may be provided for different styles of radiators and different vent opening arrangement. Where there is no 75 space in the radiator coil the discharge tube may project out to one side and then be reflected back between adjacent coils of the radiator.

80 While we have described the device as a radiator attachment it is to be understood that the invention is not limited to such a particular embodiment. The steam supply for the device may be taken from the steam main instead of from the radiator if so desired.

85 In a vacuum system vent opening 60 will of course be omitted.

The concave formation of the ends of thermal element 65 is advantageous in securing quick and positive operation. The structure of the thermal element per se may however, be varied within the scope of our invention.

90 95 We do not intend to be limited to the precise details of construction nor to the particular embodiment shown and described.

We claim:

1. In a device of the class described a 100 chamber having an inlet for connection with a source of steam and an outlet, a valve controlling said outlet and means for automatically opening said valve with a rise in temperature.

2. In combination, a radiator, an outlet 105 for discharging steam therefrom, and means for automatically opening said outlet with a rise in temperature.

3. In a device of the class described, a 110 chamber having an inlet or connection with a radiator, said chamber having a steam outlet and an air vent and means for automatically closing said air vent and opening said steam outlet.

4. In a device of the class described a 115 chamber having an inlet for connection with a radiator, said chamber having a steam outlet and an air vent and common means for automatically closing said air vent and opening said steam outlet.

5. In a device of the class described, an 120 inner shell, an outer shell, an inlet extending between the shells and entering said inner shell near the top, a head closing the top of the inner shell, said head having a steam outlet, a valve controlling said outlet, said valve having a vent opening, means controlling said vent opening and said steam outlet, and means for delivering steam from 125 said outlet into the room.

6. In a device of the class described, a chamber having an inlet for connection with a source of steam and an outlet, a valve controlling said outlet, means for automatically opening said valve with a rise in temperature, and means for varying the temperature at which said valve opens.
7. In combination, an enclosing shell having an inlet for connection with a radiator, 10 said shell having an outlet port, a yieldably seated valve member controlling said port, said valve member having an air vent and a thermally sensitive element disposed in said shell and having a valve stem for closing said air vent and opening said yieldably seated valve member.
8. In combination, an enclosing shell having an inlet or connection with a radiator, 20 said shell having an outlet port, a yieldably seated valve member controlling said port, said valve member having an air vent, a thermally sensitive element disposed in said shell and having a valve stem for closing said air vent and opening said yieldably
- seated valve member, a return from said shell to the radiator, and a check valve controlling said return. 25
9. In combination, an enclosing shell having an inlet for connection with a radiator, a head member closing the upper end of said shell, a valve housing mounted in said head member, said valve housing having a steam outlet port, a valve member controlling said port, a plug mounted in said valve housing, a spring interposed between said plug and 30 said valve member and urging the valve to its seat, an air vent port in said valve member, and a thermally sensitive element disposed in the shell and having a valve stem 35 cooperating with said valve member upon expansion of the thermally sensitive element to close said air vent and open said steam outlet. 40

In witness whereof, we hereunto subscribe our names, this 5 day of July, 1923.

CLARENCE E. FRAZIER.
HELMER R. LINDQUIST.
